POUCH FOR HOSIERY OR SIMILAR ARTICLE

Joe E. Adamson, Port Chester, N.Y., assignor to Prepac, Inc., Bronx, N.Y., a corporation

Filed Aug. 17, 1964, Ser. No. 81,316

Term of patent 14 years

(Cl. D87—5)

FIGURE 1 is a rear perspective view of a pouch, for hosiery and similar article showing my new design;

FIG. 2 is a rear elevational view thereof;

FIG. 3 is a front elevational view thereof; and

FIG. 4 is an enlarged cross-sectional view thereof taken on the line 4—4 of FIG. 3, a portion of the section being omitted for convenience of illustration.

I claim:

The ornamental design for a pouch for hosiery or similar article, substantially as shown and described.
